[57] CLAIM

The ornamental design for a table, as shown.

DESCRIPTION

FIG. 1 is a perspective view looking down at one longitudinal side of the table;

FIG. 2 is a side view looking at the opposite side of the table from that shown in FIG. 1;

FIG. 3 is a perspective view looking up at the bottom of the table and showing one end and one longitudinal side of the table;

FIG. 4 is an end view looking at the end opposite that shown in FIG. 3; and

FIG. 5 is a top plan view of the table.
